UNITED STATES PATENT OFFICE

LÉON A. DANCO, OF FAIRFIELD, CONNECTICUT, ASSIGNOR TO MCKESSON & ROBBINS, INCORPORATED, OF BRIDGEPORT, CONNECTICUT, A CORPORATION OF CONNECTICUT

DESIGN FOR A TOILET BOX OR SIMILAR CONTAINER

Application filed October 12, 1929. Serial No. 33,020. Term of patent 14 years.

To all whom it may concern:

Be it known that I, LÉON A. DANCO, a citizen of the United States, residing at Fairfield, county of Fairfield, State of Connecticut, have invented a new and original Design for a Toilet Box or Similar Container, of which the following is a specification, reference being had to the accompanying drawing, forming part thereof.

I claim:

The ornamental design for a toilet box or similar container substantially as shown.

LÉON A. DANCO.
